UNITED STATES PATENT OFFICE.

RICHARD MAXWELL EATON, OF NIAGARA FALLS, NEW YORK.

ELECTRIC FLASH LIGHT.

Application filed August 2, 1926. Serial No. 126,401.

This invention relates broadly to electric flash lights of the kind in which a cylindrical casing containing the electric battery is closed at one end with a cap containing the lens, reflector and lamp and at the other end with a cap containing, generally, a coil spring adapted to force the battery terminal forwardly in engagement with the electrical contact on the lamp. These caps are usually 10 removably secured to the respective ends of the casing by a threaded connection therewith. More specifically the invention relates to the last mentioned cap.

One object of the invention is the provision 15 of means whereby the flash light may be readily suspended or carried upon the person. Accordingly an irregular metallic loop is swivelled on the flash light and this loop is so proportioned as to be readily slipped over 20 a button and moved axially so that the thread or shank of the button as the case may be is engaged by a portion of the loop of decreased diameter, the button serving to prevent the accidental removal of the loop. The flash 25 light may also be suspended from a finger say, by passing the same through that portion of the loop of increased diameter which is proportioned to receive it.

The invention also has for its object the 30 provision of a cap which will permit the flash light to stand on end when the suspension loop is pivoted thereon. According to this aspect of the invention the end face of the cap is substantially a plane surface which 35 is formed with a depression of the shape of the suspension loop and of a depth sufficient to permit the loop to lie wholly within the outer marginal surface so that it will not interfere with the balance of the flash light 40 when stood on end.

The invention also seeks to automatically 45 retain the suspension loop in the recess when not in use. It also seeks a construction wherein the loop may be readily released and automatically moved to operative position substantially perpendicular to the end surface of the flash light. With these ends in view the loop is formed of resilient metal, such as wire, and the cap is formed with a 50 shoulder or cam surface in non-parallel or reverse relation with a portion of the loop, whereby when the loop is pressed into the depression, it is sprung over the shoulder which then overties the loop and retains it within 55 the depression. When the loop is to be moved out of the depression, the thumb nail, for in-

stance, may be inserted beneath the end of the loop to raise a portion over the shoulder when the resilience of the metal will cause the said portion of the loop to override the 60 shoulder and spring the loop to a substantially vertical position.

The invention also resides in a suspension loop which is practical from the standpoint of ease and cheapness in manufacture and 65 convenience in use.

These and other objects of the invention and the means for their attainment will be more apparent from the following detailed description of a preferred embodiment, illustrated in the accompanying drawings, in 70 which:

Fig. 1 is a view in elevation showing a conventional type of flash light to which the invention is applied. 75

Fig. 2 is a view showing the suspension loop applied to a flash light cap which is recessed to receive the loop when in folded position.

Fig. 3 is a view in elevation of the cap, 80 partly in vertical section, taken in the plane indicated by the line 3—3 in Fig. 2 and showing the suspension loop lying within the outer marginal surface of the cap end.

Fig. 4 is a fragmentary sectional view taken in the plane indicated by the line 4—4 in Fig. 2 and showing the cam surface or shoulder formed along the edge of the depression over which a nonparalleled portion of the suspension loop is sprung to retain it within 90 the depression. 85

A common type of electric flash light shown in Fig. 1 comprises a cylindrical casing 5 closed at the one end by a threaded cap 6 carrying the lens 7 and closed at its other end by a threaded cap 8. The cap 8 is formed with a plane end surface 9 whereby the flash light may be stood on end and with a polygonal shaped rim 10 serving as a convenient grip in screwing or unscrewing the cap from 100 the end of the casing. Pivotaly mounted in the cap 4 at one side thereof is a suspension loop of irregular outline indicated in general at 11. The loop is preferably formed of resilient metallic wire and is of largest diameter between the portions 12—12 whereby it may be slipped over a button or carried on the finger and of a reduced diameter between the portions 13—13 adjacent to the end 20 so that axial movement of the loop after it has 110 been slipped over a button will bring the shank or other securing means thereof with-

in the part of reduced diameter where the button will prevent its displacement. The ends 14 of the loop are turned inwardly as shown to pivot within holes in a relatively 5 raised portion such as the straight sides of a depression 15 formed in the end surface 9 of the cap 8 of a depth sufficient, as shown in Fig. 3, to permit the loop to lie wholly below the marginal surface 9 and not interfere with 10 the balance of the flash light when stood on end. Thus the loop is movable from either of the positions shown in full lines in Figs. 1 or 2 to the position shown in dotted lines in Fig. 2 and in Fig. 3.

15 The loop 11 is retained automatically within the depression 15. To effect such retention the straight portions 16—16 converge from the ends 14 while the marginal edges 17 of the recess 15 are disposed in non-parallel relationship with respect to the portions 16 being spaced further apart at the points 18 than the cooperating points 19 of the sides 16 of the loop. As the loop is moved into the 20 depression, the portions 16, being resilient, spring under the edges 17 and are retained thereby. To displace the loop from out the depression and cause it to assume a perpendicular position, as shown in Fig. 1, the thumb nail may be inserted under the end 20 25 of the loop, as it lies in the recess, while the flash light is grasped in the palm of the hand with the fingers encircling it. As the end 20 is raised, thus turning the loop about its pivots, the shoulders 19 ride over the edges 17 30 and the converging sides 16, being resilient, and being expanded away from one another by the edges 17, have a tendency to spring back into normal position, which causes the portions 16 to slide along the diverging edges 35 40 17 and move the loop to a vertical position.

It will thus be seen that a clip or suspension ring has been provided attached to a flash light case or fitting thereof which has an irregular shape substantially similar in form to 45 that used in garter fastenings so that the flash light may be suspended thereby or attached to a button on the clothes of the user. Moreover, the suspension loop does not interfere with the balance of the flashlight, when it is 50 stood on end, since the loop is retained, when not in use, within a depression formed in the end of the flashlight casing. The loop is also adapted to be automatically returned to operative position by a simple releasing action 55 which may be effected by the thumb nail of the hand holding the flashlight.

Various modifications may be made in the 60 location, configuration and composition of the suspension ring as well as in the means whereby it is retained within the depression in the casing and the means whereby it is moved to operative position. Furthermore, the several features of the invention are capable of independent use as well as in combination and no 65 limitation is intended by the phraseology of

the foregoing description or illustrations in the accompanying drawings beyond that set forth in the appended claims.

I claim:

1. As an article of manufacture, the combination of a cap for a flash light and an elongated suspension loop varying in width transversely, said cap having a plane end surface formed with an irregular depression to receive the loop and of a depth sufficient to permit the loop to lie within the marginal surface of the cap, said loop being pivoted on the cap and being formed with oppositely disposed straight sides adjacent the pivots and converging therefrom, said depression having oppositely disposed straight edges adjacent the pivots and the walls of the depression beneath the edges being recessed. 70 75 80

2. The combination of a cap for a flash light adapted to serve as a base for the flash light when the same is stood on end, and a suspension loop for said flash light pivoted on said cap and foldable from a collapsed inoperative position to a non-collapsed flash light supporting position, said loop comprising a resilient body bent upon itself adjacent its mid portion and diverging therefrom to its ends, and an irregular shaped channel formed in said cap corresponding to the shape of the loop for receiving and housing the loop when the same is in collapsed inoperative position, said loop having its ends turned inwardly and forming pivots for the loop, and said channel being provided with undercut portions for receiving the diverging portions 95 100 105 of the loop adjacent their inturned ends.

3. The combination of a cap for a flash light adapted to serve as a base for the flash light when the same is stood on end, and a suspension loop for said flash light pivoted on 105 said cap and foldable from a collapsed inoperative position to a non-collapsed flash light supporting position, said loop comprising a resilient body bent upon itself adjacent its mid portion and diverging therefrom to its ends, and an irregular shaped channel formed in said cap corresponding to the shape of the loop for receiving and housing the loop when the same is in collapsed inoperative position, said channel having its opposed portions provided with means for engaging the loop to cause it to snap into and out of inoperative position. 110 115

4. The combination of a cap for a flash light, and an elongated suspension loop pivoted thereon, said cap having a plane end surface formed with a channel corresponding in shape to the loop and of a depth to snugly receive the loop below the surface of the cap, said channel having undercut walls adjacent the pivots of the loop for maintaining the loop in inoperative position within said channel. 120 125

5. The combination of a cap for a flash light, and an elongated suspension loop piv- 130

oted thereon, said cap having a plane end surface formed with a channel corresponding in shape to the loop and of a depth to snugly receive the loop below the surface of the cap,
5 said channel having undercut walls adjacent the pivots of the loop for maintaining the loop in inoperative position within said channel, the portions of the channel adjacent the

pivots of the loop being spaced apart an amount unequal to the spacing of the sides of the loop requiring the loop to spring into and out of the channel. ¹⁰

In testimony whereof I have hereto affixed my signature on this 28th day of July, 1926.

RICHARD MAXWELL EATON.
